UNITED STATES PATENT OFFICE

2,568,536

APPARATUS FOR FILLING AND RAMMING
FOUNDRY FLASKSAustin Sidney Beech, Leighton Buzzard, England,
assignor to Foundry Equipment Limited, Leigh-
ton Buzzard, England, a British companyApplication March 10, 1949, Serial No. 80,679
In Great Britain January 28, 1949

9 Claims. (Cl. 22—36)

1

The present invention relates generally to apparatus for filling flasks with moulding sand. More particularly, the invention relates to such apparatus in the form of a ramming head of the type (hereinafter referred to as the type described), by means of which sand is projected into the flask, comprising a substantially cylindrical casing having a lateral inlet for sand and a peripheral outlet which, when in use, is directed downwards, and a rotor that is rotatable in the casing for projecting sand through the outlet.

Various constructions of high-speed, motor-driven sand-filling units or ramming heads constituting apparatus of the type described have heretofore been proposed, in which the rotor had a single blade operative during rotation to form the sand in the casing into wads and project the wads through the casing outlet, which blade was slightly concave in the direction of its rotation. In one such proposed construction, a curved blade lying tangentially to the rotor-body had two end walls, one adjacent to each side of the casing, one of which was for shearing sand from the stream fed into the casing, and the other for preventing forward displacement of the sand, both of which end walls were spaced away from the casing.

These proposed ramming heads delivered the wads of sand intermittently with a time interval between each two successive wads depending on the speed of rotation of the rotor, and the present invention has for one of its objects to enable a more continuous or substantially continuous stream of sand to be projected by a ramming head of the type described independently of the speed of rotation of the rotor.

Another object is to increase the output of sand from a ramming head of the type described as compared with that of a head of the same size having a single bladed rotor driven at the same speed.

A further object is to provide, in a ramming head of the type described, a bladed rotor of improved construction as described hereinafter for producing a substantially continuous stream of sand propelled by the head.

According to a feature of the present invention there is provided a ramming head for projecting moulding sand into flasks, comprising a substantially cylindrical casing having in a side wall a lateral inlet for sand, and having a peripheral outlet which, when in use, is directed downwards, and a rotor that is rotatable in the casing for projecting sand through the outlet, which

2

ramming head is characterised in that the rotor is provided at its periphery with a plurality of projector devices arranged to be operative in succession to project sand through the outlet. 5 The projector devices may be situated in a circle coaxial with the axis of rotation of the rotor, and may be so arranged that, when the rotor rotates, they sweep successively past the inlet and successively deliver sand through the outlet of the casing.

Preferably, the projector devices constitute each a projector vessel, each of which vessels is so arranged that, when the rotor rotates, it is placed successively in open communication with 15 the inlet and outlet of the casing.

The rotor may be constituted by a paddle-wheel-like structure having the projector devices at its periphery spaced angularly equally apart one from another about the axis of rotation of 20 the rotor.

According to another feature of the invention, each projector device is mounted on the body of the rotor so as to be movable towards and away from the internal peripheral face of the casing.

25 Preferably, the projector devices are constituted by end portions of impellers of elongated form, and releasable attachment means is arranged to fix each impeller to the rotor, which attachment means, when released, permit the impellers to be adjusted endwise in relation to the internal peripheral face of the casing, and enable them to be rigidly fixed in their position of adjustment.

Conveniently, the rotor has a plurality of substantially tangential seats arranged spaced apart 35 one from another around its axis of rotation, and the attachment means adjustably secure the impellers each to one of said seats.

Each impeller and its projector device is preferably of U-section, and has its side limbs of 40 different depth with the deeper side limb situated adjacent to side wall of the casing having the inlet.

The improved ramming head may comprise a 45 central hollow support, whereof the larger part constitutes a gear box, and the smaller part has the rotor journaled on it, a drive shaft that extends through said support and has one end in driving connection with the rotor, and gearing in the gear box for driving the drive shaft and the rotor.

According to yet another feature of the invention, the rotor has only two projector devices situated diametrically opposite one another.

One embodiment of the invention and a modi-

ification thereof are diagrammatically illustrated by way of example, and not by way of limitation, in the accompanying drawings, wherein:

Figure 1 is a perspective view showing one construction of ramming head according to the invention with its cover plate shown open and the wearing plate removed;

Figure 2 is a vertical transverse section taken on the line 2-2 in Figure 3, and

Figure 3 is a front elevation of the head partly in section after removal of its cover plate and wearing plate;

Figure 4 is a detail view showing a rammer blade or impeller detached from the rotor, and

Figure 5 is an end view of the impeller shown in Figure 4;

Figure 6 is a diagrammatic view of a modified construction of rotor.

Like reference characters designate like parts throughout the several views.

Referring first to Figures 1 to 5, a substantially cylindrical casing, designated generally 10, comprises a side wall 12 carried by a central hollow support 14, 16, an arcuate peripheral rim or wall 18, and a cover plate 20 of dished formation which may be hinged, as at 21, to the rim 18. Preferably an annular wearing plate 22 shown in section in Figure 2 but omitted from Figures 1 and 3 for the sake of clarity lies parallel with the side plate 12 and bears against or is integral with the rim 18 which may have a liner 19. These parts may be secured together in any convenient or known manner.

The central hollow support comprises an external part 14 constituting a gear box, and an internal tubular part 16 which is formed as or provided with the inner race of an anti-friction roller bearing 24, whereof the outer race is carried on or constituted by a hub 26 of a rotor described hereinafter, which hub has an end flange 28. A two-diameter impeller drive shaft 30, 31 extends through the central hollow support, whereof the inner end part 31 is reduced and constitutes a stub shaft which drives the rotor. An end plate 32 has a boss 34, by which it is secured on the stub shaft 31 by a nut 36. This end plate 32 has a marginal portion that is secured by studs 38 to the flange 28 of the hub 26, and has an annular rib 40 on which the flanged end of the hub 26 is seated. The other end of the hub has within it a ball-bearing 41. The outer end of the gear box 14 is journaled by an anti-friction bearing 42 on the larger part 30 of the impeller shaft. Any convenient means may be provided for driving the impeller shaft. As illustrated, a bevel pinion 44 fast on the shaft in the gear box meshes with a bevel gear wheel 46 which may be driven in any convenient manner.

The gear box 14 is considerably wider than it is deep.

The upper part of the casing has in the side wall 12 a lateral inlet at 48, and a downwardly-directed outlet is provided at 50. The inlet is preferably provided with a hood or cowl 52, immediately below which is arranged feed means for supplying sand into the casing. As shown in broken lines, this feed means may comprise a conveyor of the endless member type having a belt 53 running over a roller 54.

The rotor has a circular hollow body portion 56 that is fast on the hub 26, and has within it a plurality of substantially tangential seats 58 that are spaced apart equally about its axis of rotation and carry each an impeller 60, of elong-

ated form and of U-shaped channel section as described hereinafter. As illustrated, there are two seats 58 and two impellers 60 situated diametrically opposite one another, but if desired the rotor may have three, four or five seats, or, as shown in Figure 6, six seats, each carrying an impeller. Each seat 58 has in it a U-section slot for receiving its impeller, and each impeller 60 is adjustably secured in position in its seat by attachment means comprising a nut-equipped stud 62 or like fastener that extends into the seat and adjustably clamps the impeller rigidly in position in relation to the internal peripheral face of the casing, which face may be provided by the liner 19.

Each impeller 60 has an end portion that is situated adjacent to the rim 18 or its liner 19, and is a projector device constituting a projector vessel. Preferably the two side limbs 64 and 66 of the channel are of different depth, the deeper limb 64 being situated adjacent to the side wall 12 having the sand inlet 48, and being arranged slanting outwards slightly as shown in Figures 2 and 5, so that, when in use, it will sweep past the inlet, and will exert a shearing action on the stream of sand entering the head through the inlet 48. The bottom wall 68 of each impeller forms a blade, and when the rotor, which is a paddle-wheel-like structure, is driven at a high speed, each projector vessel receives sand at the inlet 48 and projects it through the outlet 50, thereby producing a continuous stream of sand for filling and ramming foundry flasks and the like. Owing to each impeller being adjustable longitudinally on its seat, wear of each projector vessel can be readily taken up. After opening the cover plate 20 access to the fixing screws 62 of the impellers can be had through the opening at 70 at the middle of the wearing plate 22.

Various modifications may be made in the details of construction described above without departing from the invention. For example, in some cases the impellers may be flat or concave blades without the side limbs of the channel-shaped members 60 described above. Also, in some cases the wearing plate 22 may be omitted, and if so the cover plate constituting a side wall of the casing will be dished less than as shown in the drawings.

I claim:

1. A ramming head for projecting sand into flasks comprising a circular casing, a co-axial rotor therein and at least one straight channel shaped impeller blade of uniform cross-section throughout its entire length and having an operative part and an inoperative root part carried by the rotor, the root part of the blade being clamped within the rotor by releasable clamping means, the operative part projecting outwardly from the rotor towards the circular periphery of the casing, the clamping means being such that the blade is adjustable lengthwise to compensate for wear of the free end of the operative part of the blade, the casing being provided with a lateral inlet for sand close beside the path of the operative part of the blade and with a peripheral outlet.

2. A ramming head as set forth in claim 1 wherein the seat within the rotor are slot-like to accommodate the blade root and the root being held rigidly in the seats when adjusted by a bolt screwed through the rotor to bear against the blade root.

3. A ramming head as set forth in claim 1 wherein the impeller blade slopes backwardly

with respect to the direction of motion of the rotor.

4. A ramming head for projecting moulding sand into flasks comprising in combination a circular casing having an inlet in one side close to the outer part of the casing and a peripheral outlet, a hollow rotor co-axial with the casing and having its hollow interior accessible from one side, at least one impeller blade on the rotor, said impeller blade being of rectilinear channel-like form in cross-section and being substantially straight longitudinally and said rotor being slotted in its periphery; to fit the blade and enable it to enter the interior of the rotor but project therefrom toward the periphery of the casing, a seating for said blade within the rotor and clamping means within the hollow part of the rotor to hold said blade on said seating.

5. A ramming head as claimed in claim 4 characterized by the fact that said seating is non-radial with respect to the casing and the rotor to hold the blade in a position at an angle to the radius of the casing and rotor.

6. A ramming head as claimed in claim 4 wherein said seating and the blade held thereon are non-radial with respect to the casing and rotor, said blade having its channel side leading with reference to the direction of rotation of the rotor.

7. A ramming head according to claim 4 in which the seating and blade supported thereby are tangential to a circle within the rotor.

8. A ramming head according to claim 4 fur-

10
5

ther comprising a door for a side of the casing adjacent the open side of the rotor.

9. A ramming head according to claim 4 in which the seating and blade supported thereby are tangential to a circle within the rotor, the flanges of the channel blade projecting forwardly in the direction of rotation of the rotor, and the blade sloping rearwardly with reference to such direction of rotation.
